J. NOLL.

SOUND RECORDING APPARATUS,
APPLICATION FILED FEB. 3, 1914.

1,118,219.

Patented Nov. 24, 1914.

UNITED STATES PATENT OFFICE.

JOHN NOLL, OF NEW YORK, N. Y., ASSIGNOR TO AMERICAN TELEPHONOGRAPH CORPORATION, OF WILMINGTON, DELAWARE, A CORPORATION OF DELAWARE.

SOUND-RECORDING APPARATUS.

1,118,219.

Specification of Letters Patent. Patented Nov. 24, 1914.

Application filed February 3, 1914. Serial No. 816,158.

To all whom it may concern:

Be it known that I, JOHN NOLL, a citizen of the United States, residing at New York city, in the county of New York and State 5 of New York, have invented certain new and useful Improvements in Sound-Recording Apparatus, of which the following is a specification.

My invention relates to electrically controlled sound recording apparatus whereby a message may be automatically recorded at a telephone station, and my object is to provide a means whereby the operator at the central office may supervise the entire operation 10 of the sound recording apparatus. The means whereby I accomplish this result consist, broadly, of a polarized relay at the telephone station, the movements of the relay operating to start or stop the driving mechanism which actuates the recording cylinder and the recorder. Simultaneously with 15 the movement of the relay the recorder is connected to or disconnected from the telephone circuit. A means is provided at the central office whereby the operator can control the movement of the relay, a signal indicating instantly to the operator whether or not the controlling circuit is operative. The recording circuit is, by the operation of 20 the polarized relay, connected to or disconnected from the talking circuit, a signal in the cord circuit instantly notifying the operator at the central office whether the recorder is connected or disconnected.

35 In the accompanying drawing, the figure is a view in elevation of the entire apparatus.

A polarized relay 2 is provided at a telephone station 3, one of the purposes of 40 said relay being to control the mechanism indicated at 6, 8, 9 and 10, which actuates the recording cylinder 7 and the recorder 1, as hereinafter more fully described.

The armature 2^a, pivotally mounted at 2^b, 45 is adapted to close the motor circuit when placed in operative position, the current starting from batteries 4 and passing through the motor 6 to contact 2^c, to its adjacent contact 2^d, of relay 2, and back to 50 the batteries 4. The above described circuit actuates the motor 6 which, by means of the pulley 8, belt 9 and driving pulley 10, operates the recording cylinder 7 and the recorder 1. Simultaneously with the action 55 of the armature 2^a and of the control-

ling circuit contacts 2^e and 2^f the swinging contacts 2^g, 2^h, 2ⁱ and 2^j connect the recording circuit with recorder 1 to the telephone circuit at the points 5^a and 5^b. The recorder 1 having been connected across the 60 telephone circuits at the points 5^a and 5^b, the recording cylinder 7 may be incised by sound vibrations. Said connection operates a signal 29 in the cord circuit at the central office notifying the operator that the 65 recorder 1 is in circuit in the talking circuit, as hereinafter more fully described.

The operation of the polarized relay 2 is controlled by the movements of two switches 11 and 12. The armature 2^a of relay 2 is 70 rendered operative by a positive current controlled by the switch 11.

A ground 13 is connected to the negative side of the batteries 14, the positive side of said batteries being connected to the signal 75 15, to a contact 11^a, to its adjacent contact 11^b of switch 11, to the tip 16^a of the connecting plug 16, to the adjacent contact 17^a of jack 17 and connected at the point 18 to the winding of the relay 2, and thence to 80 the ground 19.

The armature 2^a of relay 2 is rendered neutral by a negative current controlled by switch 12. The ground 13 is connected to the positive side of the batteries 20, the 85 negative side of said batteries being connected to the signal 21, to the contact 12^a, to its adjacent contact 12^b of switch 12, to the contact 11^c, to its adjacent contact 11^b of switch 11, to the tip 16^a of the connecting 90 plug 16, to the adjacent contact 17^a of jack 17, connecting at the point 18 to the winding of the relay 2 and thence to the ground 19.

The operator's connecting cord circuit is 95 of the common battery type, comprising batteries 40 grounded at 22 and connected to the negative side of the batteries 40 and to repeating coils 24 and 25 at the points 23 and 26. When the operator places the plug 16 in the jack 17 the talking circuit of the plug 16^a and 16^b is connected to its adjacent contacts 17^a and 17^b of the jack 17. The signal circuit is connected at the sleeve 16^c of the plug 16 to the sleeve 17^c of the jack 17. 100

When the plug has been inserted in the jack the signal 29 indicates the connection, and when relay 2 has been placed in operative position the signal 29 indicates that the recorder 1 is connected. The current from batteries 40 passes through one of the wind- 105 110

ings of the repeating coil 25 to relay 38 through the contacts 12^a and 12^b of switch 12, through the contacts 11^a and 11^b of switch 11 to the ring 16^a, to its adjacent contact 17^b, to the point of connection 5^a, to the contact 2^a, to its adjacent contact 2^b of relay 2, through the winding of the recorder 1, back to the contact 2^a, to the contact 17^a, to its adjacent contact 16^a, to the contact 11^b, 5 to its adjacent contact 11^c of switch 11, to contact 12^b, to its adjacent contact 12^c of switch 12, to one of the windings of the repeating coil 24, and back to the batteries 40. Simultaneously with the connection of the 10 plug to the jack a signal current passes from the batteries 40 to the point of connection 27, to a resistance coil 28, to the lamp 29, to the sleeve of the plug 16^c, to the sleeve of the jack 17^c, and to the ground 30. The 15 current passing through the lamp 29 illuminates it. When the recorder circuit has been closed by relay 2, the current of the talking circuit closes relay 38, closing contacts 38^a and 38^b. The closing of these contacts shunts the current from the lamp 29 through a lower resistance than the lamp 31. The action of the remaining half of the cord circuit is identical with that hereinbefore described, with the exception of 20 the function of switches 11 and 12. The current from batteries 40 passes through one of the windings of the repeating coil 25 to the relay 41, to the ring 32^a of the plug 32, through an external circuit back 25 to the tip 32^b of the plug 32, to the winding of the repeating coil 24 and thence to the batteries 40. Simultaneously with the connection of plug 32 the current passes from the batteries 40 to the connection 27, to a 30 resistance 33, to the lamp 34, to the sleeve 32^c of plug 32 and thence to a ground in the external circuit. When the relay 41 is actuated by closing an external circuit through the ring 32^a and tip 32^b of the plug 32 the contacts 35 and 26 close, shunting lamp 34 through the resistance 37.

The apparatus hereinabove described accomplishes two results. The sound recording mechanism, comprising the recorder, recording cylinder and the motor for actuating the same is installed in the office of 35

party A. Party B, desiring to record a message thereon, calls the central office operator from a telephone station. The operator thereupon makes the requisite connection for actuating the recorder through its motor, the signal lamps indicating to the operator when such connection is established and likewise indicating the disconnection upon completion of the message 60 transmitted by party A.

Having thus described my invention, I claim:

1. In an electrically actuated sound recording apparatus, a sound recording mechanism, comprising a recorder and recording cylinder and means for actuating the same, means for electrically controlling said sound recording mechanism, and means for indicating the connection and disconnection of the circuits controlling the operation of said sound recording mechanism, substantially as described. 65

2. In an electrically actuated sound recording apparatus, the combination of an 70 electrical recorder, a recording surface adapted to register the impulse transmitted to said recorder, a relay adapted to control the action of said recording mechanism, and a plurality of connecting plugs, one of 75 which is connected to said relay and adapted to be actuated by a starting and stopping means located in circuit between said plugs, substantially as described.

3. An electrical recording mechanism, 80 comprising a relay adapted to control said mechanism, an electric sound recorder, means for connecting and disconnecting said recorder in the talking circuit, a plurality of connecting plugs, one of which is connected to the talking circuit, and a signal 85 means connected in the cord circuit of said plugs, said connecting and disconnecting means being adapted to actuate said signal means, substantially as described. 90

In testimony whereof, I affix my signature 95 in presence of two witnesses.

JOHN NOLL.
